ABSTRACT

Laterally spaced vertical securing members in the form of telescoping tubes support respective sides of lining panels extending therebetween. The outer tubular support member is formed by a pair of U-shaped members whose vertical flanges extend outwardly therefrom in the plane of the panels, lie face-to-face and carry hooks which extend at right angles away from the flanges at their outer edges on both sides of the outer support member. Slots within the panels of a width in excess of the hooks and at positions corresponding to the hooks permit the panels to be hung thereon. The panels terminate in L-shaped recesses at their edges and an L-shaped vibration dampener is sandwiched within the recess and between the panel and right angle wall portions of the outer vertical tubular support member.

The inner telescoping tubular member may be slotted at the top at right angles to the plane of the panel supported thereby, and a plate is welded within the slot and to the upper deck to securely position the vertical support member. U-shaped backing spacers having a lengthwise dimension corresponding to the lateral width of the partition and lining are slotted adjacent both ends to receive the hooks and retain adjacent vertical support members at desired spaced intervals.

SHIP PARTITION AND LINING CONSTRUCTION

BACKGROUND OF THE INVENTION

1. Field of the Invention

This invention relates to the interior construction of a ship and in particular to the construction of the partition and lining for the same.

2. Description of the Prior Art

Ships and other marine vehicles are subject to external forces caused by the pitching and rolling of the hull while at sea and by vibration from the engine and the like, and this may result in substantial deformation to the portions of the ship. Therefore, the interior equipment within the ship must be so constituted as to withstand considerable forces and deformations.

SUMMARY OF THE INVENTION

It is the general object of this invention to provide a partition and lining for a ship which can withstand the forces produced and the deformation of the ship while operating at sea and permitted to operate in a stable state. In particular, the partition and lining of the present invention is characterized by employing vertically telescoping members such as an outer post member, which carries an inner securing member at the top with vertically extending plates at both sides of the post, forwardly extending hooks being provided at the outer edge of the extending plates defined preferably by the flanges of face-to-face U-shaped members forming the post and leaving a suitable space between the hooks and the sidewall of the post U-shaped portion. The rear of the lining or partition panel at both edges is provided with slots correspondingly positioned and opposite to the hooks with the horizontal width of the slots being considerably greater than the thickness of the plate of the hook. The base portion of the post and the top portion of the securing member are fixed and welded to the upper surface of the lower deck and the lower surface of the upper deck, respectively, and thereafter the lining or partition panels are connected to the posts by engaging the hooks with the slots of the panels. Preferably, a vibration proof member is inserted between the contacting parts of the panels and the posts. The securing member is slidably telescoped into the upper portion of the post and carries a slot, preferably at right angles to the plane of the panels, and a positioning plate is welded at its top edge to the lower surface of the top deck of the ship with its lower portion in sliding engagement with the slot of the securing member permitting control positioning of the post. After precise positioning of the post, the securing member is welded to the positioning member at the area surrounding the slot. Backing spacers constituting a portion of the partition and liner panels determine the spacing between the adjacent posts supporting the partition and liner panels with the backing spacers having a lengthwise dimension corresponding to the lateral width of the partition and liner panels to be installed between posts, with each backing spacer including transverse slots located adjacent the ends for receiving the hooks to retain the adjacent posts at desired spaced intervals.

BRIEF DESCRIPTION OF THE DRAWINGS

FIG. 1 is a schematic elevational view of the improved ship partition and lining construction of the present invention.

FIG. 2 is an enlarged view, in section, of a portion of the partition and lining construction of FIG. 1.

FIG. 3 is vertical, sectional view of a portion of the construction of FIG. 1.

5 FIG. 4 is a perspective view, partially broken away, of a portion of the construction of FIGS. 1-3.

FIG. 5 is a perspective view, of a modified arrangement of the ship partition and lining arrangement of the present invention, showing a method of welding the 10 vertical posts in position after properly locating the same.

FIG. 6 is a perspective view of a partition construction of an alternate embodiment of the present invention with parts broken away as installed in a manner 15 forming an alternate embodiment of the present invention.

FIG. 7 is an enlarged cross sectional view taken about line VII—VII of FIG. 6.

FIG. 8 is an enlarged cross sectional view taken about 20 line VIII—VIII of FIG. 6.

FIG. 9 is an enlarged front view of a partition of the type illustrated in FIG. 6.

DESCRIPTION OF PREFERRED EMBODIMENTS

25 Referring to the illustrated embodiment of FIGS. 1-4 inclusive, the schematic illustration of FIG. 1 shows an inner sectional view of a ship, wherein numeral 1 designates the lower deck, 2 the upper deck, 4 a post vertically supporting lining panels 3 provided between the lower and upper decks. A baseboard 5 is provided at the lower part of the panel of lining plate 3, a ceiling 6 being secured to the lower part of the upper deck 2. The details of this embodiment of the invention are illustrated in FIGS. 2-4 inclusive which is constituted essentially by lining panels 3 and the posts 4. The post 4 is constituted by an outer rectangular tubular support member 11 and a telescoping upper securing member 13 carrying the support member 11 at the top thereof. In this embodiment, preferably member 13 is elastically 40 and frictionally contacted with the inner surface of the support member 11 by a suitable spring (not shown). Essentially, the support member 11 is formed by two abutting U-shaped members in which vertical flanges 22 extending along both sides of the U-shaped members form vertically extending plates 14. At the outer edges of the plates 14, which extend in the plane of the panels and outwardly of the support member 11 at vertically spaced positions, hooks 15 which extend at right angles to the flanges 22 are formed, the hooks defining slots 23 which face upwardly and providing a defined space between the hooks and the plates 14. Each lining panel 3 is so constructed as to hold core member 17 between the surfaces of metal plates 16 on each side thereof. An edge member 18 which is of modified S-shaped configuration, in cross section, is secured between the plates 16. The edge member 18 is provided with a slot 19 on the rear surface of the same at each position corresponding to each hook 15 of the support member 11. The width of the slot is substantially greater than the thickness of the hook 15 and the lining panel 3 is adjustable to a certain extent with respect to the hook portion. In this respect, vibration proof members 20, which are illustrated as being generally L-shaped in configuration in cross section and which may be formed of a material such as rubber or the like, are secured to the upper portions of the slots of the edge member 18 in order to absorb vibration and to provide 50 55 60 65

an air-tight construction for the assembled partition and lining. In the illustrated arrangement, the partition and lining is formed by an assembly method which comprises the steps of securing the base portion of the vertical support member 11 to the lower deck 1 of the ship by welding the same thereto as an initial step. The upper securing member 13 is pulled upwardly in a telescoping manner and is secured to the bottom surface of the upper deck by similar welding or the like, whereby the post 4 is securely fixed in vertical position between the decks. Vibration proof members 21 are then positioned between both edges of the lining panel 3 and the support member 11, and the hooks 15 engage with the corresponding slots 19, respectively, thus the lining panel 3 is thereby supported by the support member 11.

In the partition and lining arrangement of this embodiment, since the support is supported by a separable, telescoping upper securing member 13, even if the ceiling or deck vibrates under forces applied to the ship while at sea, there is never an excessive force applied to the post and the lining or partition is supported in a stable state. By the employment of the hook and the slot between the lining and partition panels and the vertical posts, since the width of the slot is wider than the thickness of the hook, under complex deformation, such as changes in position or deformations between supports, the deformations are canceled by the movement of the slot portion to the right or the left on the hook. Thus, excessive force is never applied to the lining or partition panel. As described above, in this embodiment of the invention, even if complex deformations are caused at the upper and lower decks while at sea, damages of the lining panels and the supports or the partition panels caused by excessive force is thereby prevented and the lining and partition panels are maintained in a stable state even at inclined portions of the deck subject to camber and shear and the like.

Turning next to the embodiment of FIG. 5, it is well known that due to violent pitching or rolling of vessels and ships during travel, the ships are subjected to very large forces and oscillations in conjunction with the operation of the ship's engine, which results in unexpected warps or variation in position of the structural members of the vessel. Partitions and liners thus must be installed in such a manner as to provide substantial stability and rigidity to the structure in order to withstand such severe conditions. In accordance with the embodiment of the invention illustrated in FIG. 5, stability and rigid installation of the partitions and linings result primarily from the accurate position of the posts sustaining the partitions and liners. In addition, the manner of rigidly connecting the partitions to respective suspension means for the posts is critical. Normally, metallic screws, bolts and nuts cannot be employed for this purpose. Turning to FIG. 5, the arrangement of the present invention in the illustrated embodiment comprises the use of a securing member 13 which is of tubular form and telescopes within the support member 11, in this embodiment like elements being given like numerical designations to those appearing in the embodiments of FIGS. 1-4 inclusive. In this respect, the support member 11 has supported thereon by the employment of the hook and slot means, a plurality of lining panels indicated generally at 3. In this case, the securing member 13 is telescoped into the

upper portion of the support member 11 and extends upwardly therefrom. At the very top of the securing member 13, there is provided a transverse slot 24 which extends generally at right angles to the plane of the plates 14 of the outer tubular support member 11, the slot 24 receiving the lower end of a positioning plate 25 which is of a thickness approximating the width of the slot 24 within which it is received. The upper edge of the positioning plate 25 abuts the bottom surface of the upper deck 2 and is rigidly secured thereto by a weld indicated at W in substantially right angle vertical relation, further, the positioning plate 25 is oriented correspondingly to slot 24, that is, at right angles to the plane of the plates 14 of the support member 11. Thus, consistent vertical alignment of each post with respect to each lining panel 3 is achieved by laterally sliding and shifting the post along the positioning plate 25 which is first welded and fixed to the bottom surface of the upper deck 2 from which it depends. Thus, after positioning each post in the proper position, the positioning plate 25 is welded to the securing member 13 in the area surrounding the slot 24 by weld designated W'.

By contrast, in the prior embodiment, the post is illustrated as being directly welded to the lower deck while the telescoping securing member 13 forming a part of the vertical support member defined by these elements is in turn welded to the bottom surface of the upper deck prior to the installation of the partition and liners. Obviously, after installation, positioning of the posts cannot be compensated to eliminate errors.

In accordance with the present invention in the embodiment shown in FIG. 5, however, this problem is overcome, concurrently assuring rapid and precise positioning installation of partition and liners without the need for marking on the upper deck prior to installation as well as enabling the presetting of the posts. As a result, the time required for installation of the partition or lining panels is substantially reduced.

Turning next to FIGS. 6-9 inclusive, a third embodiment of the present invention is illustrated for further securely and accurately installing the partition and liner panels within a ship or vessel in a rapid and efficient manner. In contrast to the prior art installation systems, in which considerable marking on the posts being used is generally required in order to achieve accurate positioning and spacing of the posts, the present invention in the embodiment illustrated eliminates the need for marking which is time consuming and, further, as result of slight errors in the location of the marks which are often found in the field assembly, there is much time and labor required for compensation because of the oscillation and rolling of the vessel. Reference to FIGS. 6-9 inclusive illustrates the present invention as being applied to an assembly in which a plurality of support members 11 of similar configuration to the prior embodiment and wherein like numerals designate like components, are vertically spaced and support therebetween panels such as lining panels 3 at front end or rear locations as desired. In this respect, a plurality of hooks 15 are spaced along and rigidly secured to the lateral extensions for vertically extending plates 14 of each support member 11. The present invention is directed to the employment of a plurality of backing spacers 26 which have a lengthwise dimension corresponding to the lateral width of the partition and the liner panels to be installed thereby such as at 3,

each of the backing spacers 26 being comprised of a U-shaped metal member and being provided with transverse slots or cut outs 27 through the sidewalls 28 which are connected at the top by base 30. The slots or cut outs 27 are located adjacent the respective ends of the backing spacers and in effect define the lateral spacing of the support member 11, since the cut outs or slots 27 receive hooks 15 to retain the adjacent support members 11 at desired spaced intervals.

The backing spacers 26, when assembled, constitute a portion of the lining panels such as 3 installed thereby. The hooks 15 are adapted to engage within openings 19 located in the partition and lining panels 3 to support and retain the partition and liner panels in place in the identical manner of the previously described embodiments. Securing members 13 are telescoped into the upper portion of the support member 11 and are slotted at their upper ends at right angles to the plane of the post plates 14 and the lining panels 3 and receive the bottom edge of positioning plate 25 whose upper edge as in the embodiment of FIG. 5 is welded to the bottom surface of the upper deck 2, prior to welding the securing member 13 to the positioning member 25 as in that embodiment.

In this respect, when the vertical positioning of the support member 11 has been suitably controlled, the positioning or adjusting plates 25 are welded to the securing member 13 adjacent the slits 24 to securely fix the partition and lining panels 3 in a vertical position. In accordance with the present invention, in this embodiment, the desired accurate span between the adjacent posts is provided by simple marking in the field since lateral positioning of the support member 11 is achieved slowly by fitting the cut outs or slots 27 of the backing spacers 26 on the hooks 15 secured to the lateral extensions or vertical plates of each support member 11, the lengthwise dimension of the backing spacers corresponding to the desired lateral width of the spacing between posts and the corresponding lateral width of the partition and the lining. Thus, the problem of tolerance variation is substantially eliminated, engaging the hooks 15 rigidly secured to the support member 11 with the cut outs 27 of the backing spacers 26. The lower ends of the support members 11 are welded to a floor channel 29 which is in turn welded to the surface of the floor or lower deck 1 so as to provide alignment of the support members and also lateral displacement thereof. It is to be noted that the backing spacers 26 provide a certain amount of reinforcement to the partition and lining to achieve more rigid and stable preset assembly which is particularly advantageous when the lining panels 3 are loaded with a wash bowl, cup receivers and other desired attachments.

From the above, it is obvious that in the multi-embodiment of the present invention, a ship's interior may be prefabricated to reduce the construction or assembly processes in the field, to effect uniformity and promote quality in the final ship's partition and lining and to shorten the date of delivery while improving living conditions within the ship and improving the ability of the ship construction to cope with possible fire. The partitions formed in the multiple embodiments of the present invention are such that the work can be done at the camber and shear portions in the ship by a method of assembly which is quite suitable thereto, errors in the field may be readily corrected, especially in changing the width without necessarily modification to

the panel itself, the backing or furring strips and the like are not required in the instant construction, the thickness of the wall may be readily adjusted in terms of the places where the partitions are being used, and the object of the same, the relative deviations in hull configuration and location are taken into consideration and even if twisting of the hull and the like occurs, the surface of the panels is not readily affected thereby. Further to the above, it is apparent that the design of the interconnected parts is unique and the coupling generally is hidden, fire protection is enhanced by the sealability and the vibration absorption characteristics of the packing or vibration dampener material between the panels and the posts, and since the panels are coupled to the posts on one side only, the lining and finish of the panel may be readily prefabricated on one side of the panel, that being opposite to the side having the slots for engagement with the hooks carried by the post.

What is claimed is:

1. In a partition and lining construction for a ship including horizontally spaced, vertically oriented posts extending upwardly from a lower deck and supporting respective ends of laterally extending panels, the improvement wherein:

each post comprises a rectangular tubular support member and a securing member which is telescopically received within the upper end of said support member,

means fix respective ends of said securing member and said post to said upper and lower decks, respectively,

each post includes vertical plates which extend laterally to each side thereof,

a plurality of vertically spaced hooks are carried by each vertical plate and extend outwardly from its edge thereof at right angles thereto and form an upwardly open slot therebetween,

slots are formed within said panels at positions corresponding to said hooks, said slots being wider than the thickness of said hooks to provide limited lateral movement therebetween, and

means define an L-shaped recess within the end of each panel facing a corresponding corner of said post, and a vibration absorbing member is positioned within said recess and captured between said panel and right angle corner surfaces of the post.

2. The partition and lining construction as claimed in claim 1, wherein each panel comprises: metal plates spaced by a core, S-shaped end members extending between said plates at respective ends of said panel, and wherein said slots are formed within the side of said S-shaped end members at the inner half thereof, and the outer half of said end member is open and forms said recess.

3. The partition and lining construction as claimed in claim 1, wherein said securing member comprises: a rectangular tubular member slotted at its upper end at right angles to the plane of said vertical plate, and wherein said means for fixing said securing member to said upper deck comprises: a positioning plate having its lower end received by said slot, and its upper edge abutment welded to said upper deck.

4. The partition and lining construction as claimed in claim 3, wherein said means for securing said tubular posts at their bottom to the lower deck comprises a

channel member and welded to said deck with its open face extending parallel to said panel members and receiving the bottom of said posts.

5. The partition and lining construction as claimed in claim 1, further comprising: backing spacers extending between adjacent posts, each backing spacer comprising a sheet metal member having slots at each end at right angles to the longitudinal axis of the same, said slots receiving said hooks to accurately control the lateral spacing of said posts and said partition and lining panels carried thereby.

6. The partition and lining construction as claimed in claim 5, wherein said backing spacers comprise inverted U-shaped metal members having corresponding aligned slots within said sidewalls at respective ends and wherein said posts have vertically spaced hooks extend away in opposite directions along edges of both vertical plates, and wherein slots of respective sidewalls of said backing spacer receive corresponding hooks which extend outwardly from said posts to each side thereof.

7. In a partition and lining construction for a ship including horizontally spaced, vertically oriented posts extending upwardly from a lower deck and supporting respective ends of laterally extending panels, the improvement wherein:

each post comprises a rectangular tubular support member and a securing member which is telescopingly received within the upper end of said support member,

means fix respective ends of securing member and said post to said upper and lower decks, respectively,

each post includes vertical plates which extend laterally to each side thereof,

a plurality of vertically spaced hooks are carried by each vertical plate and extend outwardly from its edge thereof at right angles thereto and form an upwardly open slot therebetween,

slots are formed within said panels at positions corresponding to said hooks, said slots being wider than the thickness of said hooks to provide limited lat-

eral movement therebetween, and wherein, backing spacers comprising a sheet metal member having slots at each end at right angles to the longitudinal axis of the same further receive said hooks to accurately control the lateral spacing of said posts and said partition and lining panels carried thereby.

8. The partition and lining construction as claimed in claim 7, wherein said backing spacers comprise inverted U-shaped metal members having corresponding aligned slots within the sidewalls thereof at respective ends and wherein vertically spaced hooks extend in opposite directions along edges of both vertical plates and wherein slots of respective sidewalls of said backing spacer receive corresponding hooks which extend outwardly from said post to each side thereof.

9. A method for accurately locating a partition or lining for a ship comprising:

welding positioning plates to the bottom surface of an upper deck at laterally spaced locations and at right angles to the plane of the partition to be supported thereby,

positioning a plurality of horizontally spaced, vertically oriented posts carrying a telescoping securing member within the upper end of the same and wherein said securing member is slotted at its upper end in a plane corresponding to the plane of the positioning plate to be received thereby on said lower deck at positions generally corresponding to the positions of said positioning plates, and extending said telescoping members such that said slot within each securing member receives the lower end of a respective positioning plate, and

shifting said posts and the securing member carried thereby along the plane defined by the positioning plate and at right angles to the plane of the partition to be supported thereby, until properly positioned, and welding each positioning plate to its securing member at the engagement area of said slot and said plate, and welding the bottom of each post to said lower deck.
